MAIL BOX

Thomas J. Mrenza, Detroit, Mich.

Application October 30, 1956, Serial No. 619,241

2 Claims. (Cl. 232—17)

This invention relates to an improved mail box and more particularly to such mail box made from sheet metal by stamping operations.

Considerable difficulties are experienced by virtually every household with respect to receipt of mail and newspapers. The size of many national magazines distributed through the mail is rather large and requires for their receipt a mail box of such a large size as to be impractical. In addition, although local newspapers are usually delivered by newsboys living in the vicinity and having a "newspaper route," a considerable number of newspapers, particularly those sent out of town, is still distributed through the mails. A magazine or a newspaper which cannot be put in a mail box or put inside the front door or handed to some person in the household is usually left on the porch. In case of rain such magazine or newspaper lying in a pool of water even for a short time becomes so soaked in water as to become very heavy and difficult to dry.

Conventional mail boxes also possess a number of disadvantages even with respect to first class mail, particularly in the construction of their covers intended to make such boxes waterproof. With the cover and its hinge being necessarily located at the top of the box, such hinge presents the danger of leakage of rain water into the box. A large number of constructions, including mail boxes with double covers have been devised, seeking to eliminate this difficulty. Yet the problem of providing a completely waterproof mail box and particularly one adapted to receive not only first class mail but also magazines and newspapers is still not fully solved, all in spite of the fact that this problem has persisted for many years and its difficulties and disadvantages are faced daily by many millions of people.

One of the objects of the present invention is to provide an improved mail box whereby the above difficulties and disadvantages are overcome and largely eliminated, and a mail box is provided which, in spite of its relatively small size and compactness, is capable of receiving not only the first class mail but also magazines and some newspapers.

Another object of the present invention is to provide a mail box capable of supporting larger newspapers such as Sunday issues and thus keeping such papers out of pools of water in case of rain.

A still further object of the present invention is to provide an improved mail box of the foregoing character, having a hinged cover so constructed that the hinge is completely concealed from view and is also fully shielded from the rain water as well as water directed from the sides or the front of the mail box as may be in the case of lawn watering water hose.

A still further object of the present invention is to provide an improved mail box of the foregoing nature, which box is made from sheet metal by stamping operation and from only two sheet metal pieces or blanks and a piece of wire for the hinge, and yet possesses a number of various novel constructional features per-

A 2

forming functions making the mail box operate in its entirety in a greatly improved manner.

Further objects and advantages of this invention will be apparent from the following description and appended 5 claims, reference being had to the accompanying drawings forming a part of this specification, wherein like reference characters designate corresponding parts in the several views.

Fig. 1 is a perspective view illustrating my improved 10 mail box affixed to a wall.

Fig. 2 is an enlarged sectional view taken in the direction of the arrows on the section plane passing through the line 2—2 of Fig. 1.

Fig. 3 is a fragmentary sectional view showing the 15 top portion of the mail box including the concealed hinge and the visor covering the same, with the cover of the box being shown in its fully open position.

Fig. 4 is a view partly in section taken in the direction of the arrows on the section plane passing through the 20 line 4—4 of Fig. 2, and showing the righthand corner of the mail box.

Fig. 5 is a sectional view taken in the direction of the arrows on the section plane passing through the line 5—5 of Fig. 2.

Fig. 6 is an exploded view illustrating all of the 25 parts required for constructing my improved mail box, namely, two flat blanks of sheet metal and a straight piece of wire.

Fig. 7 illustrates the method of assembling the mail 30 box to connect the cover to the box by inserting the hinge wire through the hinge curls and trapping the wire in place by bending the side wing or flange.

Fig. 8 is a fragmentary perspective view showing one 35 of the flanges on the visor covering the hinge of the cover.

It is to be understood that the invention is not limited in its application to the details of construction and arrangement of parts illustrated in the accompanying drawings, since the invention is capable of other 40 embodiments and of being practiced or carried out in various ways. Also, it is to be understood that the phraseology and terminology employed herein is for the purpose of description and not of limitation.

In accordance with the invention I provide a mail 45 box which is adapted to receive a magazine folded longitudinally and first class mail either directly into the box or into the folded magazine. By such an expedient the size of the mail box required to receive a magazine is reduced to one-half of what would be required to receive an unfolded magazine. The previously proposed mail boxes intended to receive unfolded magazines had to be made in a size of virtually a suitcase. In addition, my improved mail box is so constructed 50 that the hinge connecting the cover to the box is completely concealed from view and is fully covered and protected from being reached by rain water or even water from a water hose. In the mail boxes of conventional construction provision of a hinge at the top thereof not only presented the danger of leakage of rain water but also a place where rust would soon appear, making the mail box rather unsightly. I also provide a novel construction whereby my improved mail box can be made of sheet metal from a minimum number 55 of pieces, namely, two sheet metal pieces or blanks and a straight piece of wire and yet produce a construction including a large number of novel features not found in conventional mail boxes, and producing greatly superior operation of the mail box.

In the drawings there is shown by way of example 60 one embodiment of the present invention. Referring specifically to the drawings, my improved mail box 65 comprises generally a box B of downwardly converg-

ing shape and a cover C connected to the box by a hinge H concealed under the visor 10. The box B comprises a back wall 11, a front wall 12, end walls 13 and 14, and a bottom 15. The back wall 11 is made of greater height than the front wall 12 and, therefore, the end walls 13 and 14 have their upper edges sloping down toward the front wall 12, as is best shown in Figs. 2 and 7.

The back wall 11 extends upwardly further than the general outline of the box B to provide an upstanding flange 9 which is, in effect, a continuation of the wall 11 above the general outline of the box B, and a downwardly and forwardly bent visor 10, the front portion of which is bent upon itself as is best shown in Figs. 2 and 3 at 16. The portion 16 extends toward the back wall 11 for a substantial distance, and the back edge thereof is provided with hinge curls 17 to form a portion of the hinge.

The cover C comprises a flat portion 20 having downwardly depending flanges 21 and 22 along its end edges, and a downwardly depending flange 23 along its front edge. Along the back edge of the flat cover portion 20 there is provided an upwardly extending flange 24. Along the upper edge of the flange 24 there are provided curls 25 complementary to the curls 17 of the portion 16. A straight piece of wire 30 passed through the aligned curls 17 and 25 completes the hinge connecting the cover C to the box B.

By virtue of the construction disclosed above, the hinge H is disposed well under the visor 10, and above the front edge thereof.

The flanges 21, 22 and 23 of the cover C overhang the end walls 13 and 14 and the front wall 12 of the box B, thus completely enclosing the upper edges thereof and directing rain water downwardly on the outside of the box. The visor 10 has at its ends downwardly depending flanges 26 and 27 overhanging the ends of the cover flanges 21 and 22 as is best shown in Fig. 4. By virtue of such a construction, entry of the rain water into the box at the back corners thereof is prevented.

It should be appreciated that the flanges or tabs 26 and 27 may be regarded as downward continuations of the visor 10 or as forwardly directed protrusions of the upstanding flange 9 and the top portion of the back wall 11. Obviously, the tabs 26 and 27 may be made as continuations of either of these portions or may be made as separate pieces and secured to said portions in any desirable manner. In the present embodiment of the invention, the flanges or tabs 26 and 27 are made as a continuation of the upstanding flange 9 and of the top portion of the back wall 11, as is best shown in Figs. 6 and 7. However, I do not wish to be limited to such a construction since the important consideration is the provision of such flanges 26 and 27, rather than how they appear in the blank. Draining holes 35 are provided in the bottom 15 of the box and beaded screw or nail holes 36 are provided in the upper portion of the back wall 11, as shown. Location of the screw or nail holes 36 is such that they can be conveniently reached with a screw driver or a hammer when the cover C is open. Spring clips 40 are riveted or otherwise secured to the bottom 15 of the box and extend upwardly as shown in the drawings, being thus adapted to support bulky newspapers such as a Sunday paper. A latch 41 which may be of a type commonly used in suitcases may be provided for securely locking down the cover C.

It is preferable to have the box B between 12 and 16 inches in length and approximately 7 inches in its median height. The width of the box at the bottom should be made preferably between 1 and 2 inches, and at the top between 3 and 4½ inches. A box of such proportions takes all magazines folded longitudinally, i. e. along the middle line parallel to its bound side, virtually all first class mail with the exception of some unusual packages, small parcel post packages, as well as newspapers received

by mail and folded in a manner customary for such a newspaper. The clips 40 can support the more bulky newspapers and prevent them from becoming soaked while lying on a porch. It should be appreciated that even if such newspaper remains outside of the box during a rain but off the floor of the porch, the rain water will drain relatively quickly from it and, unless the rain continues for many hours, it normally will not absorb as much water as it would lying in a pool of water, and, therefore, it can be dried more quickly.

Figs. 6 and 7 illustrate my improved method of making the improved mail box disclosed above. In accordance with invention, I provide two sheet metal blanks generally designated by Bb and Cb and a piece of wire 30. The portions of the blanks formed into portions of the mail box are designated by the same numerals as the respective portions of the formed mail box with a letter b added to indicate that the respective portion is still in blank form.

The box blank Bb comprises the back wall portion 11b, the bottom portion 15b, the front wall portion 12b and the end wall portions 13b and 14b. The back wall portion 11b has at its top a portion 9b, visor portion 10b, and the portion 16b provided with a number of tabs 17b intended to be bent to form the curls 17. Tabs or hinges 26b and 27b are also provided as sidewise continuations of the portions 9b and of the upper part of the back wall 11b. Suitable flanges are provided along the edges of the portions 26b, 27b, 11b, 13b and 14b to provide overlapping joints, as well as along the edges of the portions 13b, 12b and 14b which are to become upper edges of the box, thus strengthening construction of the box and making its upper edges well rounded. The portions 13b and 14b may be made as continuations of the portion 11b. However, this would result in seams being in front, and such expedient is not preferable.

The cover blank Cb comprises a flat portion 20b having flat portions 21b, 22b and 23b which are to form downwardly depending flanges 21, 22 and 23, respectively, and a portion 24b with the tabs 25b intended to form the upstanding flange 24 bent at an acute angle to the portion 20b, as is best shown in Fig. 2, to form a trough having open ends and a V cross section. Hinged curls 25 are formed along the upper edge of the flange 24.

In producing my improved mail box, I first provide blanks Bb and Cb, as shown, and a piece of wire 30. Thereupon, the tabs 17b and 25b are curled on the radius determined by that of the wire 30 to receive the same. Thereupon, the blanks are bent on lines indicated in Fig. 6 in phantom lines with the exception of one of the side tabs 26b or 27b. Some or all of the overlapping seams may be soldered or welded. I prefer to solder two vertical seams at the junctures of the portions 13b with 11b; the portions 14b with 11b; and at the front corners of the cover. I also prefer to solder the seam or the place of juncture of the portions 27b with 10b, and portion 26b with portion 10b although soldering of one of such seams is done as the last assembly operation, as explained below.

After the blanks described below are bent and soldered as explained below with the exception of one of the sides or wings, wing 26b in the embodiment illustrated (see Fig. 7), the curls 17 and 25 are aligned and the wire 30 is passed through them, thus connecting the cover C to the box B. Thereupon, the tab 26b is bent and its place of juncture with the visor 10 is soldered, thus locking the wire 30 in place. By virtue of such an expedient, while movement of the wire 30 longitudinally of the hinge may still be possible for a very short distance, coming out of the wire is prevented.

My improved mail box may be made of any suitable sheet material, particularly sheet metal, and such sheet metal may be tinned or galvanized either in sheet form, or the box and the cover may be galvanized or tinned after forming but before assembly. My improved mail

box may also be made of polished metal sheets, or it may be polished and lacquered after forming; a coat of paint or any other suitable protective layer may also be provided.

By virtue of the above disclosed construction, objects of the invention listed above and numerous additional advantages are attained.

I claim:

1. A mail receiver comprising a box open at its top, and including a back wall, a front wall, two side walls, and a bottom; an upstanding flat portion provided along the top edge of said back wall and extending upwardly therefrom for a substantial distance, a visor extending downwardly and forwardly from the upper edge of said upstanding portion and terminating forwardly and below the upper edge of said portion, a swinging cover for said box adapted to close substantially the entire top opening of said box and having along its rear edge a flange extending upwardly and forwardly, a hinge provided underneath said visor and connecting said swinging cover thereto along the upper edge of its upwardly and forwardly extending flange, the ends of said upstanding portion of the back wall and said visor extending for a substantial distance beyond the sides of said cover, and depending flanges provided on the ends of said visor and overlying the rear portion of the sides of said cover.

2. A mail receiver comprising a box open at its top, and including a back wall, a front wall, two side walls, and a bottom; an upstanding flat portion provided along the top edge of said back wall and extending upwardly therefrom for a substantial distance, a visor extending

5

10

downwardly and forwardly from the upper edge of said upstanding portion and terminating forwardly and below the upper edge of said portion, a swinging cover for said box adapted to close substantially the entire top opening of said box and having along its rear edge a flange extending upwardly and forwardly, a hinge provided underneath said visor and connecting said swinging cover thereto along the upper edge of its upwardly and forwardly extending flange, the ends of said upstanding portion of the back wall and said visor extending for a substantial distance beyond the sides of said cover, and depending flanges provided on the ends of said visor and overlying the rear portion of the sides of said cover, said hinge being formed by the front edge of said visor being turned back and upwardly upon itself and provided with hinge curls along its upper edge with the complementary curls being provided along the upper edge of the forwardly and upwardly directed flange on said cover, and a hinge shaft connecting said curls together to form a hinge, the cover and the flange along the rear edge thereof forming, when the cover is open, a trough having open ends.
